UNITED STATES PATENT OFFICE.

GEORGE H. MAAS, OF MILWAUKEE, WISCONSIN.

RECEPTACLE.

1,273,254.

Specification of Letters Patent. Patented July 23, 1918.

Application filed July 26, 1917. Serial No. 182,963.

To all whom it may concern:

Be it known that I, GEORGE H. MAAS, a citizen of the United States, residing at Milwaukee, county of Milwaukee, and State 5 of Wisconsin, have invented new and useful Improvements in Receptacles, of which the following is a specification.

My invention relates to improvements in that class of receptacles, the walls of which 10 are formed of metal and enamel, the metal being covered upon both its exterior and interior surfaces with enamel. I have found by experience that the contiguous parts of such a vessel cannot be secured together in 15 the ordinary way by bolts and flanges, owing to the fact that the enamel or other fragile material is likely to chip off or become broken, and I have therefore devised means for securing separate parts of such 20 receptacle together so as to form a water tight joint by using either solder, tin, rubber or other similar substance, which, when heated, flows into and hermetically closes all 25 joints as may occur between the contiguous surfaces of such receptacle, whereby the danger of chipping or breaking the enamel or other fragile surface is avoided.

My invention is further explained by reference to the accompanying drawings, in 30 which—

Figure 1 is a casing, forming part of the receptacle, showing my improved attachment connected therewith, the lower portion of the casing being in vertical section, drawn 35 on line 1—1 of Fig. 2.

Fig. 2 is a horizontal section of the casing, drawn on line 2—2 of Fig. 1, showing a plan view of the attaching means.

Referring to Fig. 1 of the accompanying 40 drawing, 5 is a casing which is closed at the top by the member 2, and at its lower end by the base plate 3. The casing 5 comprises the central metallic member 4, which member is provided with the enamel surfaces 6, 6.

45 It will be understood that my invention is equally adapted for securing the separate parts of any casing together, whereby an efficient seal is produced.

The casing 5 is provided at its bottom 50 with an annular flange 7, which flange is provided with an enameled coating. My securing means comprises a clamping ring 8 of an internal diameter slightly greater than the peripheral diameter of the flange, 55 and having an inturned flange 9 at its upper

edge, which is of an internal diameter slightly greater than the external diameter of the casing, whereby the ring is adapted to fit over the casing with its flange 9 lapping the flange of the casing. The ring is provided with a series of vertical spaced clamping bolt holes 10 and bolts 10', the latter passing through holes in the base 3. Located between the ring 8 and extending over the base plate 3 is a packing 13 of ordinary 60 construction.

The clamping action of the bolts 10' passing as they do, through the ring 8 into the base plate 3, has no tendency to chip off or break the enamel. When the several 70 parts above the base plate 3 have been thus assembled a quantity of molten solder, tin, rubber or other similar substance 7', adapted to flow when heated, is poured into the joints formed between the contiguous parts, whereby a seal or water tight joint is formed without danger of chipping or breaking the enamel from the supporting metal. Preparatory to pouring the molten solution by 75 which such water tight joint is formed, I 80 preferably place a mold within the casing 5. The base plate 3 is then temporarily attached. The molten solution is then poured and allowed to cool, whereby it is given the required shape shown in Fig. 1. The base 85 plate 3 is then temporarily removed for the purpose of removing the mold. After said mold has been removed, the base plate 3 is again attached and bolted in place, as shown in Fig. 1. Such mold is not shown because 90 it is removed and forms no part of my present invention.

Having thus described my invention what I claim as new and desire to secure by Letters Patent, is:—

1. The combination with a casing formed of metal, coated with enamel, of a clamping ring surrounding the open end of said casing and a solution adapted when heated to flow between said parts and form a water 100 tight joint between said casing and ring.

2. The combination of a metal casing having an out-turned peripheral flange at its open end, and an external and internal enameled surface secured to said metal, a 105 clamping ring surrounding the open end of said casing provided with an inturned flange, said inturned flange being located above and lapping the casing flange, and a solution adapted, when heated, to flow be- 110

tween the joints of said casing and clamping ring, whereby a water tight joint is formed between said casing and clamping ring.

3. The combination with a casing formed of enameled metal, having an out-turned peripheral flange at its open end, a clamping member surrounding said open end, and provided with an internal flange located above and lapping the casing flange, and 10 solder adapted to adhere to and form a tight joint between said casing and clamping ring.

4. The combination with a casing formed of enameled metal having an out-turned peripheral flange at one end, a clamping mem-

ber surrounding said lower end and provided with an internal flange located above and lapping the casing flange, solder adapted when cold to adhere to and form a water tight joint between said ring and casing, a base plate secured to the lower side of said ring, a packing located between said base plate and ring, and means for securing said base plate to said ring beneath said packing. 25

In testimony whereof I affix my signature 25
in the presence of two witnesses.

GEORGE H. MAAS.
